BOTTLE HOLDER

Henry K. Powell, Chicago, Ill.

Application October 21, 1937, Serial No. 170,163

10 Claims. (Cl. 229—16)

This invention relates to holders or containers for the packaging and transportation of bottles or similar articles.

A general object of the present invention is the provision of an improved holder or container which can be formed of paper board, or similar sheet material, as a single unitary blank, with minimum loss or waste of material, and which can be packaged and shipped in flat knocked-down condition, and can be set up by the user quickly and with facility and without requiring the use of special apparatus or additional fastenings, and which, when so set up, will have suitable strength and stability to retain a plurality of bottles or the like securely, afford them desirable protection, and permit their being carried with convenience.

Another object is the provision of a holder or container having the characteristics specified above and which holds its desired form when empty and thus facilitates the placing of bottles or similar articles in it, and also permits either some or all of the contained articles to be removed from it without necessitating any mutilation of it or involving its being disassembled or collapsed.

Another object is the provision of a holder or container having the characteristics specified above and which, with its contents of bottles, or the like, constitutes a package which is well adapted to stacking and to packing, with others of like kind, in a crate or packing case.

Other and further objects of the invention will be pointed out or indicated hereinafter or will be apparent upon an understanding of the illustrative embodiments herein shown and described.

For purpose of aiding in an explanation of the invention, I show in the accompanying drawing forming a part of this specification, and herein-after described, one form in which it may be embodied. It is to be understood, however, that this is presented merely for purpose of illustration and is not to be construed in any fashion calculated to limit the appended claims short of the true and most comprehensive scope of the invention in the art.

In said drawing,

Fig. 1 is a perspective view of a holder or container embodying the invention, same being shown in assembled condition;

Fig. 2 is a vertical section transversely through the same with a partition element in place;

Fig. 3 is a plan view of a blank, representing the container in its disassembled or flat form; and

Fig. 4 is a perspective view of a partition element which may be employed in the container.

The illustrative embodiment shown in the drawing will now be described.

The holder or container shown is formed from a sheet of paper board or other suitable material by cutting into a blank such as illustrated in Fig. 3. This is slotted and creased to provide a bottom panel 10 which, at its opposite margins, defined by creases *a*, is conjoined with side sections, which side sections respectively comprise a lower side panel 11, an upper side panel 15, and top panel 16, on the one side, and on the other side, a lower side panel 11', an upper side panel 15', and top panel 16'. Creases *d* define the junction lines of the lower and upper side panels, and creases *e* define the junction lines of the top and upper side panels.

At one end of the bottom panel 10 the blank is formed with a girth section which comprises an end wall panel 12 which remains integral with the bottom panel 10 along crease line *b*, side wall panels 20 and 20', which are integral with panel 12 along crease lines *f*, and interlocking terminal or end panels 21 and 21' which remain integral with wall panels 20 and 20' along crease lines *g*.

At the other end of the bottom panel 10 is formed a stiffening flange 14, which is flexible upwardly along a crease line *c*.

Top panels 16 and 16' are provided with similarly located apertures 17, and top panel 16' is formed with a tongue 18 extending therefrom and a slot 19 is formed along a portion of the junction line of panels 15 and 16.

Lower side panels 11 and 11' and bottom panel 10 are slightly shorter than panels 15 and 15' so that the corners of the latter form jutting shoulders 19.

Panels 20, 20', 21 and 21' are severed from the adjacent ends of the side sections and panel 21' is slotted to form a tongue 22 and panel 21 is provided with a slot 24 for accommodating said tongue.

Blanks such as above described and illustrated in Fig. 3 may be packaged in quantities, in flat form, for shipment and storage. A container is set up from the flat form by flexing the side sections upwardly from the bottom panel along the crease lines *a*, flexing the stiffening flange 14 upwardly along the crease line *c*, and flexing the girth section upwardly along the crease line *b*. Then flexing the outer wall panels 20 and 20' along the crease lines *f* to bring them into abutment with the outer sides of the lower side panels 11 and 11', then flexing the end panel 21 along

the crease line *g* and into contact with the outer surface of the upwardly turned flange *14*, and then flexing the panel *21'* along crease line *g* into overlapping relationship with panel *21*, and finally sliding tongue *22* downwardly into slot *24*. By this interlocking of panels *20* and *21*, the girth section is secured in its upright position and forms a continuous upstanding rectangular rim around the bottom panel *10* and embraces the lower side panels *11* and *11'*. The outer wall panels *20* and *20'* are approximately the same length as the lower side panels *11* and *11'*, and the girth section is of slightly less height than the side panels *11* and *11'*, as a consequence of which the corners or ledges *19* jut over the upper margins of end panels *21* and *21'* and hold them against sliding upwardly on the side panels. The lower margin of tongue *22* passes down along the inner side of stiffening flange *14*, and this, together with the fact that the corners of the girth section fit closely against the end margins of lower wall panels *11* and *11'*, holds the girth against slipping downwardly. End wall *12* and stiffening flange *14* stiffen bottom panel *10* against flexing and outer wall panels *20* and *20'* hold the side panels against falling outwardly.

The holder as thus set up affords a container having a box-like lower portion which is open at its top, and from which side panels *15* and *15'* extend upwardly. A number of bottles or similar articles may be disposed in upright position in this receptacle, resting on bottom panel *10* and having their lower parts encompassed by the upstanding walls, so that they are retained against sliding off of the bottom. The upper side panels *15* and *15'* extend upwardly at the outer sides of the bottles, and, for stacking and crating, the top panel *16* is flexed downwardly onto the tops of the bottles, top panel *16'* is flexed downwardly on top of panel *16*, and tongue *18* slipped into slot *19*, thus securing the top panels in such position. Thus the holder is provided with a flat top which is supported on the bottles and which permits a number of said packages to be stacked one upon another. As so assembled, the apertures *17* coincide and afford an opening for insertion of the fingers to facilitate lifting of the package. In order to permit the package to be conveniently carried in the hand, the top panels may be flexed to the position illustrated in Fig. 2 and the tongue *18* bent over the upper margin of panel *16*, in which disposal the apertures *17* align and admit the fingers, so that the upper portions of the top panels form a handle by which the package may be carried.

If it is desired to keep the bottles from contacting one another, a conventional form of cellular partition element, such as illustrated in Fig. 4, may be employed, same being made of paper board and having a longitudinal wall *30* and transverse walls *31* and being placed in the holder after it has been assembled as above described, where it functions also to brace the lower portions of the side sections against flexing inwardly.

It will be observed that when this device is in its set-up condition, it retains its character as a receptacle or container even though no bottles or other articles are in it. It will be noted also that one or more of the bottles may be removed from it without requiring its being disassembled and without involving any mutilation of it whatever. As a consequence, it is particularly adapted

for re-use, as for returning the empty bottles and packaging another group. It likewise forms a convenient repository for the empty bottles in the household of the consumer, thus making it easy for him to save and return the empty bottles, a service which is desired by the bottler. 5

What I claim is:

1. A container for the packaging of bottles and the like, comprising an integral sheet cut and creased to form a bottom panel with upwardly flexible side sections at its side margins and an upwardly flexible girth section conjoined to it at one end, said girth section being creased to form an end panel at said end of the bottom panel and side wall panels adapted to abut the outer surface portions of the side sections, and interlocking end wall panels, said interlocking end wall panels being engageable to connect the ends of the girth section and to form an end wall along the other end of the bottom panel. 20

2. A container of the sort described comprising an integral sheet cut and creased to form a bottom panel and a pair of side sections which are flexible to positions where they extend upwardly from opposite side margins thereof and an upwardly flexible girth section integral with one end of the bottom panel, said girth section being creased to form an end wall panel along said end of the bottom panel and side wall panels flexible into engagement with the lower outer surfaces of the upstanding side sections and terminal wall panels flexible inwardly to form an end wall along the other end of the bottom panel, said terminal wall panels being connectible to each other to secure the girth section in the form of an upstanding rim about the bottom panel and side sections and the side sections being provided at their upper ends with a handle whereby the set-up container may be carried. 35

3. A container as specified in claim 1 and wherein an upwardly flexible flange is formed integral with the end of the bottom panel opposite said end wall panel, said flange, when in upstanding position, being positioned at the inner side of the interlocking end panels and serving to stiffen the bottom panel transversely. 40

4. A container of the sort described comprising an integral sheet cut and creased to form a bottom panel and upwardly flexible side sections integral therewith along its opposite margins and a girth section integral with the bottom panel along one end thereof, said girth section being flexible upwardly from the bottom panel and being creased to form side wall and terminal panels flexible about the outer sides of the side sections and the opposite end of the bottom panel, and the terminal panels being connectible to secure the girth section in the form of an upstanding rim, at least one of the side sections being provided with an outwardly extending portion which juts over the upper margin of said rim. 55

5. A container of the sort described comprising a collapsible paper board device formed with a rectangular bottom panel having upwardly flexible side sections conjoined to its side margins, an upwardly flexible end wall panel conjoined with the bottom panel along one of its end margins, side wall panels conjoined to opposite end margins of the end wall panel and flexible into abutment with the upstanding side sections, terminal panels conjoined to ends of the side wall panels and flexible into overlapping relationship along the end margin of the bottom panel opposite said end wall panel, means being provided for securing said terminal panels to each other 70 75

to retain said end and side wall panels in upright positions, and the side sections being provided at their upper ends with a handle, said top panels being formed with apertures to afford 5 a handle whereby the container may be carried.

6. A container of the sort described comprising a sheet cut and creased to form a bottom panel integrally connected to an upwardly flexible girth section and upwardly flexible side sections which 10 are disposed opposite each other, the girth section being creased to form an end wall panel extending along one end of the bottom panel and side wall panels which are flexible into engagement with the outer sides of the side sections and 15 terminal panels which are flexible inwardly along the other end margin of the bottom panel, said terminal panels being provided with tongue and slot elements whereby they may be connected to each other, the height of said end and side 20 panels being only a fraction of the height of the side sections and the side sections being creased at a distance above the side wall panels to form top panels which are flexible inwardly into overlapping relationship at a distance above the bottom panel, said side sections being provided with 25 tongue and slot elements whereby said top panels may be secured in said inwardly flexed relationship to form a flat top for the container.

7. A container as specified in claim 6 and

wherein an upwardly flexible flange is formed integrally with the bottom panel along its margin opposite said end wall panel.

8. A container as specified in claim 6 and 5 wherein the side sections are formed with outwardly projecting portions which jut over the upper margins of the upstanding terminal panels.

9. A container of the class described comprising a sheet creased to form a bottom panel and upwardly flexible side sections at its opposite 10 sides, said side sections being provided at their upper ends with a handle whereby the container may be carried, a girth forming an upstanding rim along the margins of the bottom panel and the outer sides of the upstanding side sections 15 and serving to retain the side sections against falling outwardly, said girth being affixed to an end marginal portion of the bottom panel and having interlocking parts connecting its ends to each other, and a partition member disposed 20 within the upstanding rim and having portions extending transversely of the bottom panel and cooperating with the lower portions of the side sections to brace them against flexing inwardly.

10. A container as specified in claim 1 and including means for securing the free ends of the 25 side sections to each other when in upstanding positions.

Acting Commissioner of Patents.

to retain said end and side wall panels in upright positions, and the side sections being provided at their upper ends with a handle, said top panels being formed with apertures to afford 5 a handle whereby the container may be carried.

6. A container of the sort described comprising a sheet cut and creased to form a bottom panel integrally connected to an upwardly flexible girth section and upwardly flexible side sections which 10 are disposed opposite each other, the girth section being creased to form an end wall panel extending along one end of the bottom panel and side wall panels which are flexible into engagement with the outer sides of the side sections and 15 terminal panels which are flexible inwardly along the other end margin of the bottom panel, said terminal panels being provided with tongue and slot elements whereby they may be connected to each other, the height of said end and side 20 panels being only a fraction of the height of the side sections and the side sections being creased at a distance above the side wall panels to form top panels which are flexible inwardly into overlapping relationship at a distance above the bottom panel, said side sections being provided with 25 tongue and slot elements whereby said top panels may be secured in said inwardly flexed relationship to form a flat top for the container.

7. A container as specified in claim 6 and

wherein an upwardly flexible flange is formed integrally with the bottom panel along its margin opposite said end wall panel.

8. A container as specified in claim 6 and 5 wherein the side sections are formed with outwardly projecting portions which jut over the upper margins of the upstanding terminal panels.

9. A container of the class described comprising a sheet creased to form a bottom panel and upwardly flexible side sections at its opposite 10 sides, said side sections being provided at their upper ends with a handle whereby the container may be carried, a girth forming an upstanding rim along the margins of the bottom panel and the outer sides of the upstanding side sections 15 and serving to retain the side sections against falling outwardly, said girth being affixed to an end marginal portion of the bottom panel and having interlocking parts connecting its ends to each other, and a partition member disposed 20 within the upstanding rim and having portions extending transversely of the bottom panel and cooperating with the lower portions of the side sections to brace them against flexing inwardly.

10. A container as specified in claim 1 and including means for securing the free ends of the 25 side sections to each other when in upstanding positions.
